Attorney

UNITED STATES PATENT OFFICE.

RALPH WALTER, OF HEMPSTEAD, NEW YORK.

GAME APPARATUS.

1,256,400.

Specification of Letters Patent. Patented Feb. 12, 1918.

Application filed August 28, 1917. Serial No. 188,636.

To all whom it may concern:

Be it known that I, RALPH WALTER, a citizen of the United States, and resident of Hempstead, in the county of Nassau and 5 State of New York, have invented certain new and useful Improvements in Game Apparatus, of which the following is a specification.

This invention relates to new and useful 10 improvements in game apparatus, and it is the primary object of the invention to provide a device of this character, upon which a new and novel type of game may be played, which is very amusing, and which also employs considerable skill on the part of the 15 players. The game is played on a board, which is provided with transverse stepped grooves therein to represent trenches with firing steps, and raised portions adjacent 20 the marginal end edges of the board to represent artillery positions. Small different sized disks are arranged on the board, in 25 said positions to represent artillery, infantry, and machine gun bullets and said disks being movable as will be described.

Another object of the invention is to provide a device of this character, which is 30 easily and simply constructed, inexpensive to manufacture, and one which will be very efficient in operation.

With these and numerous other objects in view, my invention consists of the novel features of construction, combination and arrangement of parts which will be herein- 35 after referred to and more particularly pointed out in the specification and claims.

In the accompanying drawings:

Figure 1 is a plan view of the game board; 40 Fig. 2 is a side elevation of the same; and Fig. 3 is a detail transverse section through one end of the same.

In describing my invention I shall refer to the drawings in which similar reference characters designate corresponding parts 45 throughout the several views.

The game apparatus comprises a substantially rectangular shaped game board 1, being provided in one side thereof, with spaced parallel transverse grooves 2, which 50 are adapted to represent trenches. These grooves are four in number, two being spaced on each side of the transverse center of the board, and each of the grooves are provided adjacent their side wall facing the center 55 with offset portions 3 to form steps, which will be called firing steps. These grooves

and steps, run transversely the length of the board, as clearly shown in Figs. 1 and 2 of the drawings.

Extending parallel adjacent the end marginal edges of the board 1, are inverted L-shaped, angular members 4, which are secured to the upper surface of the board, and provided with flat top portions, which are adapted to designate raised portions, to 60 receive the game pieces which designate artillery. Beneath the angular members 4, in the upper surface of the board and behind the same, are spaced pockets 5, which are adapted to receive the game pieces when the 65 same are not in use.

A plurality of disks, similar to tiddledewinks disks, are used in playing this game, said disks being in three different sizes, designated by the numerals 6, 7, and 8, the 70 largest disks 6 having some designation thereon, preferably the letter B, to designate batteries or artillery, while the middle disks 7, have some designation, preferably the letter I to designate infantry. The smaller 75 disks 8 preferably are designated by the letter M to show that they are machine gun bullets.

A plurality of these disks are employed in playing the game and are used in a manner to be hereinafter more fully described.

In playing the game, two sets of disks, numbering twenty each, one being white and the other red are employed. The large disks 6, which are designated artillery, are placed 90 on the flat tops of the raised portions 4 at the end edges of the board. Two sets of medium disks 7, being likewise colored, are employed and are designated infantrymen, these sets being divided into four groups of 95 five disks each, and positioned two groups in each of the trenches on one side of the transverse center of the board. These disks are scattered along the trenches as desired. The smaller disks 8, which designate the 100 machine gun bullets, are divided similar to the other group and are placed on the firing steps 3 adjacent the tops of the trenches.

The manner of moving the disks is similar to the manner in which tiddledewinks disks 105 are moved, by jumping the same. To start the game, after the various groups of disks are in position as has been described, the first volley is fired simultaneously by the two opposing batteries. The army causing the 110 most havoc gains the privilege of the next move. If any part of a disk is covered by

a disk of the enemy, it is immediately removed from the game. All movement of the disks, is done by groups, and after the first volley, the players alternate in firing.

5 The use of the smaller disks 8, is for machine gun fire, and the groups of smaller disks are either used to shell the trenches of the opposing enemies or to repulse attack, mostly the latter. The machine gun groups 10 in the second trenches may only be used when the enemies occupy the first trench, and as all machine gun groups are considered stationary, they may be used by the possessor of a captured trench.

15 The intermediate medium disks 7, which are designated infantry, are maneuvered as follows. The charging is done by one group at a time. When charging place the disks on the firing steps and then over the top into 20 the space between the trenches adjacent the transverse center which is designated "No Man's Land." This will give the defenders in the opposite trench an opportunity to repulse the attackers. If the required five 25 disks comprising the group do not reach the trench without being eliminated from the game, these who do remain in the trench until their number is swelled to the desired five, in which case, the trench is won, 30 and a new group is formed. The defending disks remaining in the captured trenches are held as prisoners and may be freed by the trench being recaptured. Of course they are likely to be eliminated by the fire of their 35 comrades.

What is designated as the reserves, in the beginning of the game are the two infantry groups of disks 8, that are disposed in the second trench behind the first firing trench. 40 These reserves may be brought forward at any time provided there are at no time more than ten medium sized disks in the foremost trench. The same rules apply to the capturing of the second trench as the first, and 45 the side capturing both the enemy's trenches wins the game.

This game will form a very amusing, as well as fascinating game apparatus, and one which will at the present time hold the 50 interest. The maneuvering of the various disks requires considerable skill, on the part of the players. The top of the rectangular shaped board is preferably covered

with green cloth, so as to facilitate the movement used in jumping the disks. The 55 pockets 5 formed in the opposite ends of the board, are to receive the disks when not in use, so as the same will not be in danger of becoming lost.

From the above description taken in connection with the accompanying drawings, it is thought that a clear and comprehensive understanding of the construction, operation and advantages of my invention may be had, and while I have shown and described the 65 device as embodying a specific structure, I desire that it be understood that such changes may be made in said structure as do not depart from the spirit and scope of the invention as claimed.

Having fully described my invention what I claim is new, and desire to secure by Letters Patent is:

1. A game apparatus including a game board having spaced parallel transverse grooves in one side thereof, raised portions adjacent the marginal end edges of the said side of the board, and a plurality of different sized disk shaped game pieces movable on said board as specified.

2. A game apparatus including a game board having spaced parallel transverse grooves in one side thereof, one of the side walls of each groove being offset to form a step, angular members extending parallel 85 from adjacent the end edges of said side of the board, and a plurality of different sized disk shaped game pieces movable on said board as specified.

3. A game apparatus including a substantially rectangular shaped game board having spaced parallel transverse sets of grooves on opposite sides of the transverse center of one side of said board, said grooves having the side walls thereof adjacent the center offset to form a step in each groove, angular members extending upwardly from adjacent the edges of said side of the board, said board having pockets formed therein beneath the angular members, and sets of different sized game pieces movable on the board as specified.

In testimony whereof I affix my signature hereto.

RALPH WALTER.
